US00D492492S1

(12) United States Design Patent (10) Patent No.: US D492,492 S
Richard (45) Date of Patent: * Jul. 6, 2004

(54) MULTIPLE IMAGE DISPLAY FRAME
ESPECIALLY SUITED FOR DISPLAYING PHOTOGRAPHS

(76) Inventor: Lanny J. Richard, 9002 W. 88th Cir.,
Westminister, CO (US) 80021

() Term: 14 Years

(21) Appl. No.: 29/183,093

(22) Filed: Jun. 4, 2003

(51) LOC (7) Cl. 06-07

(52) U.S. Cl. D6/301; D16/326

(58) Field of Search D6/300-303, 308-314;
40/700, 711, 714-717, 721, 725, 722, 745,
754, 755, 756, 790, 798

(56) References Cited

U.S. PATENT DOCUMENTS

2,482,195 A * 9/1949 Martin 351/52
2,721,498 A * 10/1955 Gerson 351/158
3,582,194 A * 6/1971 Liautaud 351/156
D309,149 S * 7/1990 Pouilloux D16/326
5,323,189 A * 6/1994 Contreras 351/118
D377,037 S * 12/1996 Stolt D16/306
D427,622 S * 7/2000 Conway D16/326

OTHER PUBLICATIONS

"Harry Potter" photographs of glasses frame available from Touch of Class Catalog, 709 W. 12th Street, Huntington, Indiana 47542.

* cited by examiner

Primary Examiner—Janice E. Seeger

(74) Attorney, Agent, or Firm—Timothy J. Martin; Michael R. Henson; Rebecca A. Gegick

(57) CLAIM

The ornamental design of a multiple image display frame especially suited for displaying photographs, as shown and described.

DESCRIPTION

FIG. 1 is a perspective view of the multiple image display frame of the present invention;

FIG. 2 is a top view of the multiple image display frame;
FIG. 3 is a front view of the multiple image display frame;
FIG. 4 is a right side view of the multiple image display frame;

FIG. 5 is a bottom view of the multiple image display frame;
FIG. 6 is a left side view of the multiple image display frame; and,

FIG. 7 is a rear view of the multiple image display frame.

1 Claim, 1 Drawing Sheet

Fig. 2

Fig. 3

Fig. 4

Fig. 5

Fig. 6

Fig. 7